[57] CLAIM

The ornamental design for a walking-aid for plaster-of-paris cast, as shown and described.

DESCRIPTION

FIG. 1 is a bottom perspective view of a walking-aid for plaster-of-paris cast showing my new design;
FIG. 2 is a side view thereof, the opposite side being the mirror image of that shown; and
FIG. 3 is a bottom plan view thereof.

FIG. 1

FIG. 2

FIG. 3
